UNITED STATES PATENT OFFICE.

WILLIAM E. HALLETT AND FRANK KAMERER, OF NEW YORK, N. Y.

ELECTRIC SIGNALING.

No. 888,885.

Specification of Letters Patent.

Patented May 26, 1908.

Application filed May 29, 1907. Serial No. 376,355.

To all whom it may concern:

Be it known that we, WILLIAM E. HALLETT and FRANK KAMERER, citizens of the United States, and residents of New York, 5 counties of Kings and Queens, respectively, State of New York, have invented certain new and useful Improvements in Electric Signaling, of which the following is a full, clear, and exact description.

10 This invention relates more particularly to burglar alarms.

The primary object of the invention is to provide simple and efficient means whereby 15 any suitable point may be made to ring as soon as a window or other object is moved, and which when once set to close the circuit through the electric bell the latter will continue to ring until the circuit is again opened 20 by manually releasing the locking means.

A further object of the invention is to provide a device adapted for use in various connections; which when once set is positively locked and held so as to cause the bell to 25 continue to ring and at the same time positively holds the window or other object from further movement, and which is so arranged that it is not readily accessible to permit being tampered with from without the object 30 in connection with which it is used to stop the ringing of the bell or other alarm.

With these and other objects in view, the invention will be hereinafter more particularly described with reference to the accompanying drawings, which form a part of this 35 specification, and will then be pointed out in the claims at the end of the description.

In the drawings, Figure 1 is an elevation, partly in section and partly diagrammatic, of 40 one form of device embodying our invention. Fig. 2 is a vertical section on a larger scale, partly in elevation, taken on the line 2—2 of Fig. 3. Fig. 3 is a vertical section through the locking device and circuit closer taken on 45 the line 3—3 of Fig. 2. Fig. 4 is a sectional plan, partly in elevation taken on the line 4—4 of Fig. 2; and Fig. 5 is a sectional plan showing the invention as applied to a swinging member as a door, window, transom and 50 the like.

The window frame 10 may have the sliding sash 11 and may be constructed and operated in the usual manner. As shown, the window is vertically movable, and adjacent 55 to its inner edge is a device 12. This device 12 has a hollow shank 13, and on the end of

the shank 13 is a button or locking part 14, which is adapted to enter a recess or opening 15 in the window sash when the window is raised a sufficient distance to cause the recess 60 or opening to register with the part 14. This recess may have a metal bracket 16 fitting therein so as to take the strain off the wood of the window sash, and said recess is preferably located, so that the device 12 will 65 enter the same when the window has been raised a short distance but not sufficient for any one to enter through the window. The normal position of the device 12 is that shown in Fig. 4 in which position the device 70 12 is normally held by the window sash, the end 14 being rounded and of such a shape that the movement of the window will not be interfered with when raised or lowered, unless otherwise prevented as will be pre- 75 sently described. A rod 17 has one end entering an opening in the device 12 to serve as a guide for the latter at one end thereof, and the other end of said rod is secured to a bracket 18, the ends of which are fastened to 80 the window frame, and around the rod 17 is a spring 19 which normally forces the device 12 inward to cause the end 14 to enter the recess 15 when the latter is brought to register therewith.

85 For the purpose of holding the device 12 against outward movement after the end 14 is in locking engagement with the window sash, we provide a latch retaining device or bolt 20. This device 20 is slidingly held in 90 a bracket 21 secured to the window frame, and the inner end of said retaining device 20 is beveled, as at 22, and normally engages the end of a collar or flange 23 on the outer end of the device 12 when the said device is 95 in an unlocked position as shown in Fig. 4. The retaining device 20 is cut away or recessed, as at 24, to span the rod 17 and spring 19 when forced inward, and has a rod 25 on which is a collar 26. A spring 27 is 100 arranged around the rod 25 and is located between the window frame and the collar 26, so that immediately the window is raised and the recessed part 15 registers with the end 14 of the device 12, the spring 19 will 105 force said device 12 inward to enter the recess 15, and in this position the spring 27 will act upon the retaining device or bolt 20, so as to force the same inward past the collar 23 of the device 12, and will positively hold 110 the same inward until the device 20 is again released. By this means the window will

be positively held against movement and cannot be raised or lowered, as the retaining device 20 will prevent outward movement of the device 12 by engaging the outer face of 5 the flange 23 as shown in Figs. 2 and 3, and until the device 20 is withdrawn to release the device 12, at which time the device 20 may be made to engage the flange 23, which will hold the same outward against the tension of the spring 27. To secure this releasing movement of the retaining device 20, the rod 25 is provided with a handle or knob 28 on the outer end of said rod, and said handle is usually arranged convenient to the 10 window within the room. A plate 29 having a recess 29^a is secured to the window frame, and the end of the rod 25 is screw-threaded, so that the knob or handle 28 may be removed therefrom at night or at any other 15 time, thereby making it impossible to tamper with the retaining device 20 to release it from the locking device 12 from without the room. By screwing the handle 28 on the rod 25, the retaining device 20 may be 20 forced and held in the position shown in 25 Fig. 4.

To sound an alarm, we make the flange 23 of the device 12 form a part of an electric circuit, and against the window frame and 30 within the path of movement of said collar or flange 23 are the contacts 30 and 31. These contacts are included in an electric circuit 32, and this circuit includes an electric bell or other alarm 33, a battery 34 and a switch 35, 35 the latter being intended to break the circuit during the day time, or at such other time as is not desired to ring the alarm, the said switch being located at any convenient point. As will be seen when the window is 40 slightly raised as shown in Figs. 1, 2 and 3, so that the end of the device 12 will enter the recess 15 in the window sash, the circuit will be completed by the collar 23 engaging the contacts 30 and 31, and will complete the 45 circuit through the electric bell 33, battery 34, and switch 35, the said circuit being open when the device 12 is in the position shown in Fig. 4, or when the switch 35 is thrown to the position indicated by dotted lines 36, 50 Fig. 1 to open the circuit.

In Fig. 5 the part or member 37, instead of sliding as in the other figures is pivoted at 38 to the frame 39, so that as soon as the 55 said part 37, whether a door, transom or window is swung on its pivot or hinge, the device 12 will close the electric circuit and ring the alarm in substantially the same manner as already described.

From the foregoing it will be seen that 60 simple and efficient means are provided whereby a window or other object when tampered with will cause an electric bell or other alarm to be sounded; that a simple alarm is provided which may be readily applied to various forms of windows and the

like; and that when once set so as to ring the alarm, the device for closing the circuit will be positively and automatically locked against movement until the retaining device for holding the same is manually operated. 70

Having thus described our invention, we claim as new and desire to secure by Letters Patent:—

1. The combination with a movable device of contacts arranged in the path of said device, a collar or flange carried by said device and adapted to engage both contacts to complete the circuit therethrough, a bracket, a rod projecting from the bracket and having one end entering an opening in the device, a spring arranged around the rod and normally forcing the device inward, an electric circuit including a bell, a battery and a switch connected with the contacts and adapted to have the circuit completed therethrough when the device is forced inward, and a sliding spring-pressed retaining device adapted to hold the first-mentioned device against movement when the circuit is completed. 75

2. The combination with a movable device adapted to engage a moving object, contacts arranged in the path of said device, means carried by said device and adapted to engage both contacts to complete the circuit therethrough, a rod having one end entering an opening in the device, a spring arranged around the rod and normally forcing the device inward, an electric circuit including an alarm and a battery connected 95 with the contacts and adapted to have the circuit completed therethrough when the device is forced against the contacts, and an automatically actuated retaining device adapted to hold the first-mentioned device 100 against movement when the circuit is completed. 105

3. The combination with a movable device adapted to engage a movable object, contacts arranged in the path of said device, means carried by said device and adapted to engage both contacts to complete the circuit therethrough, a bracket, a rod projecting from the bracket and having one end entering an opening in the device, a spring arranged around the rod and normally forcing the device inward, an electric circuit connected with the contacts and adapted to have the circuit completed therethrough when the device is forced inward, an alarm 110 included in said circuit, and means adapted to hold the device against movement when the circuit is completed. 115

4. The combination with a window sash having a recess therein, of a device movable 120 toward the sash and comprising a hollow shank, a button arranged on one end of the shank, a flange carried by the other end of said shank, a fixed rod having one end entering the hollow shank of the device, a bracket 125

to which the rod is secured, a spring interposed between the bracket and the contact carried by the hollow shank and normally forcing the engaging button inward, fixed 5 contacts arranged in the path of the flange, an alarm, electric connections between the alarm and the contacts, a retaining latch independent of the locking device and having an enlarged end normally engaging one side 10 of the flange when the locking device is in a released position, said flange adapted to complete the circuit through the contacts, a rod forming a part of the retaining device, a bracket supporting the rod, a spring normally forcing the rod in one direction to 15 force the latch inward to hold the flange of the locking device against movement and to hold the same to cause the circuit to be completed, said rod of the latch having its outer 20 end screw-threaded, a bracket having a recess in which the screw-threaded end of the rod is adapted to fit, and a knob removably held to the end of the rod.

5. The combination with a movable object
25 having a recess therein, of a device movable
toward the object and comprising a hollow
shank having one end adapted to engage said
object, a flange carried by the other end of
said shank, a fixed rod having one end enter-
30 ing the hollow shank of the device, a bracket
to which the rod is secured, a spring inter-
posed between the bracket and the contact
carried by the hollow shank and normally
forcing the engaging end inward, fixed con-
35 tacts arranged in the path of the flange, an
alarm, electric connections between the
alarm and the contacts, a retaining latch in-
dependent of the locking device having an
enlarged end normally engaging one side of
40 the flange when the locking device is in a re-
leased position, a rod forming a part of the
retaining device, a bracket supporting the
rod, and a spring normally forcing the rod in
one direction to force the latch inward to hold
45 the flange of the locking device against move-
ment and to cause the circuit to be com-
pleted.

6. The combination with a movable object, of a device movable toward the object

to hold the same stationary and comprising a hollow shank having one end adapted to engage said object, a fixed rod having one end entering the hollow shank of the device, a bracket to which the rod is secured, a spring interposed between the bracket and the hollow shank and normally forcing the engaging end inward, contacts arranged in the path of the shank, means carried by the shank adapted to engage the contacts to complete the circuit therethrough, an alarm, electric connections between the alarm and the contacts, a retaining latch independent of the locking device having an end normally engaging one side of the shank when the locking device is in a released position, and a spring normally forcing the rod in one direction to force the latch inward to hold the shank of the locking device against movement and to cause the circuit to be completed.

7. The combination with a movable object, of a device movable toward the object and comprising a hollow shank having one end adapted to engage said object, a rod having one end entering the hollow shank of the device, a bracket to which the rod is held, a spring interposed between the bracket and the hollow shank and normally forcing the engaging end inward, contacts arranged in the path of the shank, an alarm, electric connections between the alarm and the contacts, means carried by the shank to complete the circuit through the contacts, a retaining latch independent of the locking device normally engaging the shank when the locking device is in a released position, a rod forming a part of the retaining latch, said rod of the latch having its outer end screw-threaded, and a knob removably held to the threaded end of the rod. 75 80 85 90
